US00D601967S

(12) **United States Design Patent**
Shaw

(10) **Patent No.:** **US D601,967 S**
(45) **Date of Patent:** ** *Oct. 13, 2009

- (54) **NON-COMPRESSED COMPRESSION COAXIAL CABLE F-CONNECTOR**
- (75) Inventor: **Glen David Shaw**, Conway, AR (US)
- (73) Assignee: **DS Engineering, LLC**, North Little Rock, AR (US)
- (*) Notice: This patent is subject to a terminal disclaimer.
- (**) Term: **14 Years**
- (21) Appl. No.: **29/293,220**
- (22) Filed: **Nov. 13, 2007**
- (51) **LOC (9) Cl. 13-03**

(57) **CLAIM**

The ornamental the design for a non-compressed compression coaxial cable F-connector, as shown and described.

DESCRIPTION

FIG. 1 is an isometric view of a non-compressed compression coaxial F-connector showing my new design;

FIG. 2 is a side view thereof; the opposite side and the left and right elevation views comprise mirror images thereto;

FIG. 3 is a front end view of thereof; and,

FIG. 4 is a rear end view thereof.

The internal features shown in dot-dot-dash broken lines appearing in the front and rear end views of FIGS. 3 and 4, respectively, represent unclaimed subject matter and form no part of the claimed design.
